UNITED STATES PATENT OFFICE

FRANK J. MUHLFELD, OF NEW YORK, N. Y.

FELT HAT AND PROCESS OF MAKING IT

Application filed July 5, 1929. Serial No. 376,132.

The object of my invention is a method of producing a perforated felt hat and the article produced by such method. The hat produced by my novel method has the advantage of permitting air to circulate freely from the exterior to the interior of the hat and vice versa, thus keeping the wearer's head cool without weakening the hat by the removal of material therefrom but, on the contrary, strengthening the hat and eliminating certain strains therein so that it will the better preserve its shape. Other advantages of the invention will appear from the description thereof.

The invention is illustrated in the accompanying drawings in which Fig. 1 shows a hat body shaped on a block of a size smaller than the interior of the hat after it has been finished; Fig. 2 shows the hat of Fig. 1 after cuts have been made therein; Fig. 3 shows the hat of Fig. 2 after it has been stretched over a block of a size which is to correspond with the interior of the finished hat; Fig. 4 shows the hat of Fig. 3 after it has been subjected to a steaming process, and Fig. 5 shows the hat of Fig. 4 finished and given the conventional Fedora shape. Fig. 6 illustrates a woman's hat of the type known as clipped velours having the invention applied thereto; Fig. 7 shows a velours hat not clipped having the invention applied thereto, and Figs. 8 and 9, the latter a section along the line 9—9 of Fig. 8, illustrate a hat having the invention applied thereto in a different manner and with the apertures closed by means of an ornamental braid.

The following is a brief summary of the steps to which I submit a hat body in accordance with my invention in order to produce a commercial hat:

1. Shaping the hat body on a block somewhat smaller than the one by which I give it its final shape (Fig. 1).
2. Cutting slits into the hat body without, however, removing any material from such hat body (Fig. 2).
3. Blocking the hat body on a block which is to give it its final shape, thus stretching the material and enlarging the slits cut thereinto into apertures (Fig. 3).

4. Subjecting the hat to the usual steaming process, thus causing the material to shrink and further enlarge the apertures (Fig. 4).

5. Finishing the hat, in a suitable manner to give it its final and marketable form, for instance, clipping it if it is a velours hat (Fig. 6) or ornamenting it with ribbon on the exterior (Fig. 5), or applying braid on the interior (Figs. 8 and 9).

Fig. 1 illustrates a hat body *a* which has had its crown portion stretched over a block smaller than the interior which the finished hat crown is to have. For instance, if the finished hat is to be of a $7\frac{1}{4}$ size the block would be approximate $6\frac{7}{8}$ size. For the purpose of manufacturing convenience, the brim *b* is shaped at that stage of the process.

Fig. 2 illustrates the hat body after it has been removed from the first block and after it has been provided with cuts or slits *c* provided by means of a sharp knife-edge. These cuts may be arranged in any desired manner to give such ornamental effect as the manufacturer desires to produce and may within reasonable limits be applied in any desired number.

Fig. 3 shows the hat of Fig. 2 stretched over a block *d* which gives the crown its final shape and size; for instance, a block of a $7\frac{1}{4}$ size if the first block used is of a size of approximately $6\frac{7}{8}$. The amount of stretching would be determined by the nature and tightness of the felt used. The apertures *e* are now larger than the slits *c* of Fig. 2 because the edges of the slits have pulled away from each other.

Thereafter the hat is subjected to the usual steaming process, thus causing the material of the hat to shrink. In the manufacture of the ordinary, i. e. unperforated hat, the material in shrinking becomes thinner but in my hat the material shrinks in such a manner as to become thicker as the presence of the slits *c* compels it to shrink in such manner. This thickness approaches the thickness of the original hat body. The material which ordinarily would be in the spaces delimited by the edges of the apertures *e* has served to thicken

and to strengthen the material of which the crown is made.

Fig. 5 illustrates the hat of Fig. 4 after it has been finished so as to conform to style 5 standards, being shown in such figure in the conventional form of a Fedora hat. The larger the number of apertures in such hat the more material is contained per unit of 10 surface area of the felt in the finished hat and therefore the stronger is the hat; or, conversely, the greater the number of apertures the thinner may be the material of which 15 the hat body *a* is originally made.

Every hat body by blocking, steaming and 20 finishing processes is subjected to various stresses and it is the strains produced by these stresses in the material which tend gradually to distort the finished hat and to compel a re-blocking of the same from time to time in order to restore its original neat appearance. In my hat the majority of the strains present tend to be relieved during the normal process of its manufacture by enlarging the 25 apertures, and therefore my hat will keep its shape better than an ordinary hat which has not been perforated or a hat which has been perforated merely by cutting away some of its material.

In Fig. 6 I have illustrated a woman's hat 30 provided with apertures *e'* produced in the manner hereinabove described and arranged in groups so as to produce distinct patterns. This hat may be of ordinary pounced felt or, as intended to be illustrated, of clipped velours, the body having originally been made in the manner disclosed in my United States Letters Patent No. 1,066,746, dated July 8, 1913, and No. 1,117,886 dated November 17, 1914, and finished by a clipping operation.

In Fig. 7 I have shown a hat made in accordance with my invention from a velours hat body made in accordance with the inventions disclosed in said Letters Patent without, however, having been clipped. The apertures are covered but not entirely concealed by the long velours fibres extending from the surface of the hat body.

By the shrinking of the body in the manner hereinabove described, the surface area of body is reduced, without of course reducing the number of upstanding or nap (velours) fibres, thus resulting in the production of a closer or fuller nap, thus enhancing the beauty of the nap.

In Fig. 8 I have illustrated another method in which my invention may be utilized for the purpose of ornamenting a hat without necessarily providing for ventilation. The slits *e*, *f*, *g* and *h* are so long that by the process of blocking and steaming their edges are separated very widely and such edges may be strengthened and the hat ornamented by covering such openings with ornamental material, such as braid *i* or any other suitable material affixed to the interior of the hat.

Such material, if closely woven, will prevent access of air to the interior of the hat, but if loosely woven, particularly if loosely woven of large filaments, will serve the purpose of both ornamenting and permitting ventilation.

Any and all parts of the hat may be provided with apertures in accordance with my invention. In Figs. 6 and 7 I have, for instance, shown the brim provided with such apertures. The brim will, of course, have to be stretched, or stretched and steamed, in order to enlarge the slits to form the apertures. The method of stretching the brim is so familiar to manufacturers of hats that the process of so doing need not be described here.

The edges of the slits during the stretching and steaming processes will be pulled apart and will tend to assume an ovoid form so that even the pointed ends of the apertures will gradually assume a pleasantly rounded form.

I claim:

1. In the manufacture of a felt hat the steps of cutting slits into the hat body, stretching the hat body and then subjecting the hat body to steam while the hat is closely fitted to a block, so as to shrink the material of such body.

2. In the manufacture of a felt hat the steps of blocking a hat body on a block, cutting slits into the hat body, stretching the hat body on a block of a size larger than that of the first-mentioned block and then steaming the hat while on the last-mentioned block so as to shrink the material of the hat body.

3. A hat body made of felted material provided with one or more ovoid apertures, the opposite edges of each aperture being substantially in the same plane and being spaced from one another, the material on one side of each aperture containing a large number of severed portions of original fibres and the material on the other side containing substantially the entire remainder of such original fibres, the apices of each ovoid aperture being slightly rounded to an outline attainable only by first cutting a slit into the hat body, then stretching and then shrinking such hat body.

FRANK J. MUHLFELD.
